UNITED STATES PATENT OFFICE.

FRANK SOHN, OF CHICAGO, LOUIS G. MARMION, OF VILLA PARK, AND ERIC H. GIBIAN, OF CHICAGO, ILLINOIS, ASSIGNEES TO THE VITROLITE COMPANY, A CORPORATION OF WEST VIRGINIA.

DESIGN FOR A SODA FOUNTAIN.

Application filed October 13, 1927. Serial No. 23,747. Term of patent 7 years.

To all whom it may concern:

Be it known that we, FRANK SOHN, a citizen of the United States, LOUIS G. MARMION, a citizen of the French Republic, and ERIC H. GIBIAN, citizen of the United States, respectively, residing at Chicago, Villa Park, and Chicago, in the county of Cook and State of Illinois, have invented a new, original, and ornamental Design for a Soda Fountain, of which the following is a speci-

fication, reference being had to the accompanying drawing, forming part thereof.

The figure is a perspective view of a soda fountain, showing our new design.

We claim:

The ornamental design for a soda fountain, as shown.

FRANK SOHN.
L. G. MARMION.
ERIC H. GIBIAN.
